(57) CLAIM

The ornamental design for a planter, as shown and described.

DESCRIPTION

FIG. 1 is a front perspective view of a planter viewed from below showing my design;

FIG. 2 is a rear perspective view from above;

FIG. 3 is a rear view;

FIG. 4 is a plan view thereof;

FIG. 5 is a side view thereof; and,

FIG. 6 is a front view thereof.

The broken lines showing hooks on the planter are included to show features that form no part of the claimed design.
